UNITED STATES PATENT OFFICE

2,610,744

PORTABLE FLOOR HOIST

Ralph R. Dague, Tuscola, Ill.

Application April 6, 1948, Serial No. 19,235

3 Claims.

(Cl. 212—57)

1

This invention relates generally to hoisting devices and particularly to floor hoists mounted on movable bases for utilization in garages, repair shops and the like.

The primary object of this invention is to enable a mechanic to perform lifting operations, such as, the removing of a transmission from an automobile, in a minimum of time with a slight expenditure of physical exertion.

Other objects of this invention are to provide an improved portable crane that is sturdily and durably constructed, to provide an inexpensive crane and to provide a light weight hoist that is employable for heavy duty work.

A meritorious feature of this invention resides in the provision of an adjustable boom that is carried by a mast mounted on a wheeled base, means being provided for selectively moving the boom on a vertical and horizontal axis.

Another important feature of this invention resides in the provision of convenient means for adjusting the angular positions of the boom to raise or lower the cable or hoist end of the boom relative to the work.

Another important feature of this invention resides in the provision of means manually operated for actuating a winding drum to wind the winding cable, the means being so constructed and designed that a slight amount of force applied is sufficient to lift exceptionally heavy articles.

These and ancillary objects and other meritorious features, to become more apparent upon a perusal of the following description, in view of the accompanying drawings, are attained by this invention as shown by way of example in the drawings, wherein:

Figure 1 is a side elevational view of this invention;

Figure 2 is a rear view in elevation;

Figure 3 is a top plan view thereof;

Figure 4 is a vertical sectional view taken substantially on the line 4—4 of Figure 3, and

Figure 5 is a cross sectional view taken on the plane of line 5—5 of Figure 4.

Referring now more particularly to the drawings wherein similar characters of reference designate corresponding parts throughout, the numeral 10 generally designates an improved crane, constructed, by way of example, in accordance with the principles of this invention. The crane comprises a suitable base 12, which includes a pair of channel bars or supporting bars 14 and 16, transversely joined by a support plate 18, which is welded adjacent one end of

the base. The opposite ends of the bars diverge outwardly, terminating in parallel ends, which have suitably secured thereto, wheel supporting plates 22 and 24. The plates 22 are attached parallel to the end of the supporting bar 14 and are similarly apertured to receive an axle 26 for a conventional wheel 28. In similar fashion, plates 24 are attached, as by bolt assemblies 30 or welding, to the end of the supporting bar 16 and are fashioned to accommodate a wheel 32. A forward support 34 supports a pair of parallel wheels 36 and 38, the support 34 being secured between the forward portion of the supporting bars for axial movement defining a steering assembly. The support 34 is secured to the forward junction plate 21 by a pin 40 and has an extending hinged plate 42, which terminates in loop bifurcations for accommodating a handle 44, which is attached thereto.

20 Vertically extending from the support plate 18 is a vertical support tube or mast 46 having a series of transverse boom adjusting apertures 48 provided therein adjacent the top. A boom 50 is mounted on the mast by means of a split collar 52. The boom 50 is swivelly secured within a pair of integrally extending apertured ears 56 by means of a transverse pin 54. The collar 52 is disposed at one end of a concentrically disposed elongated longitudinally slit sleeve 58, which is slidably received on the mast, and has a pair of extending apertured ears 60 and 62. A securing bolt 64 is connected to the ears 60 and 62 and has a handle rod 66 inserted in the head portion for loosening and tightening the bolt.

35 Disposed on the opposite end of the outer tube or sleeve 58 is a collar 68 having a pair of extending apertured ears 70, parallel to the ears 56. A U-shaped bracket 72 is swiveled at its open end to the ears by means of a pivot pin 74, providing a support for an adjusting mechanism or turn-buckle device for adjusting the angular positions of the boom. A rod 76, having a peened or bearing end 78 received in the bracket 72, is suitably exteriorly threaded, as at 80, for attachment to a supporting member 82 which is swivelly attached to the boom by a swivel pin 84. A wheel 86 is provided on the rod 76 for imparting rotation thereto to advance or remove the threaded end from the supporting member 82 so as to raise or lower the extending end of the boom.

40 Thus, it can be seen that the boom 50 may be moved in a horizontal plane by rotating the supporting sleeve 58 and it may be moved vertically by sliding the sleeve on the mast. Of

course, a suitable pin or bolt may be inserted in one of the apertures 48 to seat the collar 52 and position the boom. In such position, the boom is swingably disposed by loosening the sleeve 52. Yet, the outer end of the boom may be adjusted through rotation of the rod 76. Thus, the boom is vertically, horizontally and angularly adjustable to handle various loads and for sundry uses.

A sheave 90 is journaled at the outer end of the boom in an opening 92 therein. A guide sheave 94 is mounted in an upright placement adjacent the swiveled end of the boom by means of an attaching bracket 96. A pulley 98 is journaled in a cut out portion adjacent the top of the mast. A spacing pulley 100 extends from the sleeve 58. A hoisting cable 102 is trained over the pulleys and sheaves and has a terminating hook 104.

Of course, if found necessary, support standards 106 and 108 may be employed to rigidify or brace the mast in a vertical position. The standards may be bolted, as at 110, to the base plate 21 and secured by bolt assemblies or the like 112 to the top of the mast.

Suitable means is provided for actuating the cable 102 and for raising and lowering the hook 104 for attachment to the work or article. For this purpose, angle brackets 114 and 116 are mounted on the support plate 18. A shaft 118 is journaled to the brackets and supports a hoisting drum 120 around which the cable is wound and the end thereof secured. Secured on the drum shaft 118 is a sprocket wheel 122 over which is trained a chain 124. The chain 124 drivingly connects the drum shaft 118 with a driving shaft 128, journaled below to the brackets 114 and 116, by means of a smaller sprocket wheel 130 secured on the driving shaft.

The driving shaft 128 extends beyond the bracket 116 into a gear box 132 supported on the base plate 18. A pinion gear 134 is secured to the extended end of the shaft in meshing engagement with a spur gear 136, which extends from a pulley 138. A complementary hand pulley 140 is rotatably supported by a supporting or channel bar 142, having one end anchored to the base plate. A belt 144 is connected to the pulleys and transmits manual power applied to the pulley 140, through the medium of an extending handle 146, to the winding drum 120.

If desired, suitable means may be provided to brake the winding drum. The means preferred comprises a brake drum 150 secured on the drum shaft 118. A brake shoe 152 is received around the circumferential periphery of the drum and is actuated by a pivoted hand lever 154. The lever 154 is pivoted, as at 156, to an extending ear 158 of the support bar 142 and has pivotal links 160. The pivotal links 160 are adapted to move the split brake shoe 152 into gripping placement on the drum. Of course, means may be provided for locking the lever in the desired position and could comprise a catch or stop mechanism carried by the support bar 142. Also, suitable means may be provided for tightening the belt 144 and may comprise any conventional means found expedient.

Thus, it can be seen that there is provided a simple and reliable hoist that is equipped with an adjustable boom and with convenient means for winding an article gripping cable so that heavy weight jobs may be performed without fear of injury to an operator.

Since many other modifications and purposes

of this invention will become apparent to those skilled in the art, upon a perusal of the foregoing disclosure, in view of the accompanying drawings, it is to be understood that certain changes in size, style and arrangement of parts may be effected thereon, without a departure from the spirit of the invention and within the scope of the appended claims.

Having described the invention, what is claimed as new is:

1. In a portable floor hoist having a base and an upright secured thereto, an elongated longitudinally slit sleeve slidably engaged on said upright, means for clampingly positioning said sleeve at a preselected position on said upright, a boom pivotally connected to said first named means, and second means on said sleeve and connected to said boom for adjustably supporting the outer end thereof.
2. In a portable floor hoist having a base and an upright secured thereto, an elongated longitudinally slit sleeve slidably engaged on said upright, means for clampingly positioning said sleeve at a preselected position on said upright, a boom pivotally connected to said first named means, and second means on said sleeve and connected to said boom for adjustably supporting the outer end thereof, said first named means including a split collar clampingly engageable on said sleeve and having a pair of ears to which the boom is pivotally secured.
3. In a portable floor hoist having a base and an upright secured thereto, an elongated longitudinally slit sleeve slidably engaged on said upright, means for clampingly positioning said sleeve at a preselected position on said upright, a boom pivotally connected to said first named means, and second means on said sleeve and connected to said boom for adjustably supporting the outer end thereof, said first named means including a split collar clampingly engageable on said sleeve and having a pair of ears to which the boom is pivotally secured, said second means including a second split collar clampingly engageable on said sleeve and having a pair of ears for pivotally supporting a strut, an adjustable strut pivotally connected to said last recited pair of ears and having its outer end pivotally connected to an outer portion of said boom.

RALPH R. DAGUE.
